ROLLER OR CASTER

Filed April 23, 1928

Inventor:
MORRIS KURTZON

By: *E. Kunkel*
Atty.

UNITED STATES PATENT OFFICE

MORRIS KURTZON, OF HIGHLAND PARK, ILLINOIS, ASSIGNOR TO GARDEN CITY PLATING AND MANUFACTURING COMPANY, OF CHICAGO, ILLINOIS, A CORPORATION OF ILLINOIS

ROLLER OR CASTER

Application filed April 23, 1928. Serial No. 272,254.

My present invention relates to the rollers or casters that it is customary to employ upon sliding doors of different types, such as in show-cases, bookcases, telephone booths and similar articles of furniture, and this invention has more particular relation to a structure that is mounted on the door and is supported by and rolls upon a track secured to the floor of the case or cabinet below the sliding door. In the use of rollers for sliding or disappearing doors especially where the roller is secured to one of the horizontal edges of the door, it is frequently necessary, after the door has been mounted, to adjust or level the door by moving either end up or down in order to permit the same to easily slide and swing to its proper or desired position. With the present roller or caster the adjustment above mentioned may be readily accomplished by the use of simple tools so that any defects in the mill-work or construction of the door may be readily overcome.

It frequently transpires that after the door has been in use for a while it will be found that parts of the roller or caster have worked out of adjustment. The present structures of this character, so far as I am aware, are not provided with means to lock the adjustable elements in such manner that there is an interlocking of the parts which positively insures against accidental release. The known devices are limited more or less and are not dependable when subjected to the service demanded of such devices when installed in such places as telephone booths and the like where they are in constant and severe use. With these inherent defects in mind, I have devised a swiveling roller or caster that successfully solves the problem above stated, and

I have provided simple but ample means, that is readily accessible, for adjusting the spindle, and to lock it in adjustable positions in such manner that portions of the structure are interlocked and cannot become accidentally released. In addition to the foregoing I have constructed the roller or caster so that even though the door may warp or become distorted the roller will remain upon and operate along the track.

In the fabrication of a roller or caster of

this character it is desirable, from a manufacturing standpoint to make the parts as simple as possible from stampings or casting and automatic machine-made parts, and to assemble these parts cheaply by reducing the steps or operations of assembly to a minimum number.

It is therefore an object of my invention to provide a roller or caster that is effective and dependable in performing its functions and at the same time is economical to fabricate and assemble. Further objects of my invention resides in the provision of a roller or caster that embodies dependability and readiness of operation, durability in construction, simplicity and sturdiness in the formation and arrangement of the parts, accessibility for the purpose of adjustment, and the whole article is arranged, fabricated, and assembled in a novel and economical manner, which permits its being retailed for a reasonable price to the user.

I prefer to carry out my invention, and to accomplish the several objects thereof, in substantially the manner hereinafter fully described and as more particularly pointed out in the claims, reference being made to the accompanying drawings that form a part of this specification.

In the drawings:—

Figure 1 is a view in elevation of the roller or caster looking at the rear thereof and detached from the door.

Figure 2 is a vertical transverse section on line 2—2 of Figure 1 showing the device on the lower edge of a door.

Figure 3 is a vertical section on line 3—3 of Figure 2 looking in the direction of the arrows.

Figure 4 is a top plan of a fragmentary portion of the roller showing the manner of joining the spindle flange and yoke or guard.

The drawings are somewhat schematic for the purpose of disclosing a typical or preferred form in which my invention may be made and in said drawings I have employed similar reference characters to designate like parts wherever they appear throughout the several views.

The door, which is designated by the nu-

meral 5 (Fig. 2) is provided adjacent its lower longitudinal edge with a notch or recess 6, the purpose of which is to permit the swiveling of the roller or caster when the door is being moved to describe a turn or curve in the track 7 that is mounted upon the floor of the show-case or other article of furniture in which the door is mounted. The housing consists of a conical shaped casting 8 from the lower edge of which a cylindrical shaped apron or skirt 9 depends. The upper portion of the housing is frustated or truncated in order to provide a flat top portion 10, and extending laterally around the housing is a flange 11 that is apertured to receive the screws for mounting the roller upon the door. At its lower edges, upon each side of the apron, the flange is provided with lateral extensions or lips 11^a that project under the lower edge of the door to act as shelves to assist in supporting the door and thus remove some of the strain from the screws.

The truncated or upper portion of the housing is provided with an axial bore 12 that is screw-threaded to receive the exteriorly threaded adjusting sleeve 13, and the upper edge of said sleeve, which projects above the flat top portion 10, is castellated permitting it to be rotated by a suitable tool. There is a lock-nut 14 screwed onto the outer end of said sleeve so that by tightening this nut frictionally against the flat top portion 10 of the housing the sleeve may be retained in any of its adjusted positions. As will be seen in Figs. 2 and 3 the upper or truncated portion of the housing is thicker than the conical and cylindrical portions thus providing a longer bearing surface in the threaded bore for the sleeve and spindle. For the purpose of providing further means for maintaining the sleeve 13 in adjusted position, and to positively prevent its rotation, the upper thickened portion of the housing is provided with threaded lateral bores entering the same in planes at right angles to the axes of the sleeve 13 and headless screws 15 are screwed into these bores until their inner ends engage the threads on the sleeve, thus interlocking and positively preventing any rotation of the latter. Thus I have provided a roller with a caster that is adjustable as to height and is maintained in positive relation by the interlocking of the parts.

The spindle 16 of the caster is positioned in the smooth bore of the sleeve 13 so that it will readily rotate therein and at its lower end, below the lower end of the sleeve, there is an integral flange 17 between which and the end of the sleeve anti-friction balls 18 are interposed to permit easy casting or swiveling. After the spindle has been properly positioned in the sleeve 13, the upper end of said spindle is operated upon by centering-punches that form depressions in the upper end of the spindle and up-set the edge of the

metal in a lateral direction so as to provide a rim 19 at the upper end of the spindle to engage a shoulder 20 that is formed upon the inner bore of the sleeve and thus prevent the spindle falling out of the sleeve. 70

Upon the lower end of the spindle 16 a short stud 21 is formed that enters an aperture in the neck or connecting portion 22 of the U-shaped yoke and guard in which the peripherally grooved wheel or pulley 23 is 75 journaled. After stud 21 has been inserted in the aperture its end is struck with a riveting device and headed in the manner shown in Figs. 2 and 3 so as to secure the spindle and yoke in assembly. The yoke consists of 80 a strip or length of metal stamped U-shaped with its parallel arm 24 extending downwardly or depending from the connecting member 22 and the lower ends of the arms are provided with inwardly extending fingers 25 that 85 extend towards the track 7 below the periphery of the wheel or pulley and act as guides that prevent any side-slip of the wheel and assist in maintaining the wheel against dislodgment from the track. 90

Opposite portions of the arms 24 of the yoke are apertured to receive the axle 26 on which the wheel or pulley is mounted and interposed between the axle and the wheel or pulley is a raceway in which anti-friction 95 balls 28 are mounted. As will be seen, the connecting member 22 of the yoke is in contact with the under surface of the integral flange 17 of the spindle and, prior to assembling the structure with the housing the parts 100 are subjected to the action of an electric or spot-welder on each side of the spindle which operation spreads and unites the flange and connecting member as shown at 29 to further insure the positive assembly of these parts 105 and forming these parts in an integral one-piece unit.

The structure which is herein disclosed is made from castings, stampings, and parts made up on an automatic screw-machine, and the assembly of the yoke and wheel with the spindle 16 is a quick operation and may be readily accomplished in the desired manner with the economy of both time and labor so that the cost is thereby materially reduced. 110 Obviously changes may be made in the structure disclosed without departing from the principles involved. The foregoing detailed description and drawings have been given for the purpose of clearness of understanding 115 only, and no unnecessary limitations should be understood therefrom, but the appended claim should be construed as broadly as permissible in view of the prior art.

What I claim is:—

A device of the kind described comprising a housing attachable to the side of a sliding door and opening downwardly, said housing being substantially dome-shaped and having a threaded bore through the axis of the dome, 130

a threaded sleeve extending through opposite ends of said bore, a rotatable spindle carried by said sleeve, a wheel below said spindle, a yoke secured to the lower end of said sleeve and in which said wheel is mounted, and means engaged with the upper end of the sleeve and abutting the housing to lock said sleeve against rotation, said means and said sleeve being exterior to the housing for ready access.

10 Signed at Chicago, in the county of Cook, and State of Illinois, this 12th day of April, 1928.

MORRIS KURTZON.
